PHONOGRAPH RECORD SCANNING DEVICE

Lincoln Thompson, Cheshire, Conn., assignor to
 The SoundScriber Corporation, New Haven,
 Conn., a corporation of Connecticut

Application December 24, 1941, Serial No. 424,333

7 Claims. (Cl. 274—1)

This invention relates to phonographs, and more particularly to means for controlling the scanning movement of a phonograph stylus and stylus carrying arm across a record tablet.

When adjacent grooves of a phonograph record tablet are placed so close together that the depth of the groove is made relatively small in order to achieve the desired compactness of groove spacing, as in the case of compact, long playing commercial dictating machine records, and in other cases where the grooves are relatively shallow, the force holding the stylus in the desired groove becomes relatively small and may be insufficient to enable the stylus to propel the sound head with the desired force across the record tablet. Under these conditions, the sound head stylus may jump out of the desired groove position, or a relatively small disturbing force may be sufficient to throw the stylus laterally out of the groove and thus interrupt the scanning and the desired reproduction. For example, in a phonograph having a vertically pivoted tone arm carrying a reproducer with its stylus, when the direction of groove travel under the stylus makes an angle with the vertical plane including the stylus point and the pivot axis, the component of frictional force between the stylus and the record tablet laterally of the groove, may be sufficient to dislocate the stylus laterally out of its desired groove position, or the force due to an irregular groove direction or due to various other causes which are not subject to easy control, may produce a similar result. These difficulties have been found to be of special importance when reproducing from record grooves produced by an embossing rather than a cutting stylus, and particularly when the tablet is made of a plastic material.

An object of the present invention is to counteract one or more of the above difficulties and to improve the scanning or tracking movement of a phonograph stylus and the stylus carrying arm across a record tablet.

Another object is to provide a record tablet operated device of simple and compact form for efficiently piloting the scanning movement of a phonograph stylus and arm across the tablet.

Another object is to improve the scanning operation of a reproducing stylus and arm when the force tending to hold the stylus in the desired groove is relatively small or inadequate.

Another object is to guide the reproducing stylus and arm when the groove is discontinuous and it is necessary for the stylus to move across a blank space to reach the next groove.

Another object is to provide a record tablet operated scanning device of efficient form for convenient attachment to a part of a stylus carrying unit such as a reproducing head or a reproducing arm supporting the head.

In accordance with one aspect of the present invention, a bridge having an elastically flexible span, preferably of soft elastic rubber-like material, is supported in predetermined relation with a sound head stylus. Means, consisting preferably of one or more auxiliary styluses supported by the bridge, are adapted to engage and be propelled by a record tablet for piloting the scanning path of the sound head stylus. Means for supporting the ends of the bridge span, may be included in an elastically extensible or deformable loop which also includes the span and is adapted to encircle the unit carrying the main stylus and to make a gripping engagement with the unit. Means are provided at the ends of the span for spacing the span from the main stylus carrying unit to allow of free vertical flexing of the span. The one or more pilot styluses preferably project from the loop in a direction diverging from the plane thereof, the point of each pilot stylus being disposed in predetermined relation with the main stylus and being preferably outside of the vertical projection of the bridge span on the horizontal plane through said point when the main stylus is in operating position, thus permitting the pilot stylus to be placed close to the main stylus while the bridge span remains clear from interference with vibration of the main stylus.

These and other objects and features of the invention will be apparent from the following detailed description of a preferred form illustrative of the invention, in connection with the accompanying drawing and the appended claims.

In the drawing:

Fig. 1 is a side elevation showing one form of auxiliary scanning device combined with a phonograph reproducing unit.

Fig. 2 is a plan view showing diagrammatically the lateral frictional force exerted by a record tablet on a phonograph stylus.

Fig. 3 is an end elevation of the Fig. 1 arrangement.

Fig. 4 is an elevation of the auxiliary scanning device of Fig. 1.

Fig. 5 is an elevation of a two stylus auxiliary scanning element which may be provided in Fig. 4 between the lines A—A and B—B in place of the single stylus element shown in Fig. 4.

Fig. 6 is a fragmentary elevation showing the

auxiliary styluses of Fig. 5 in assembled relation with the main stylus.

Fig. 7 is a perspective view showing a different arrangement for mounting the ends of an auxiliary stylus supporting bridge from that in Figs. 3 and 4.

Fig. 8 is a side elevation of the Fig. 7 type of auxiliary scanning device in relation to a reproducing stylus.

Fig. 9 is a side elevation of the bridge span of Fig. 7.

In Fig. 1, the reproducing arm unit 1 includes the reproducing sound head 2 and the horizontal reproducing or tone arm 3, connected together by the leaf spring hinge 4 which flexes vertically to permit the head 2 to swing up or down about a horizontal axis while the arm 3 remains fixed vertically, the arm 3 being swingable about a vertical axis of rotation passing through the stationary anti-friction bearings 5, 5, which support the end of the arm remote from the reproducing head 2 which in turn supports the removable reproducing stylus 6 by the usually provided vibratory means, not shown except for the set screw 6' for clamping the stylus in its socket. Pivots 5, 5 are held in a frame fast to the chassis 8 of the phonograph. The sound head 2 may be raised or lowered by the handle 9 fast to the head. The stylus 6 engages and scans the record disk tablet 10, supported on the turntable 11, the groove under the stylus being fed from left to right in Fig. 1, in a direction away from the vertical axis 5, 5.

On account of the friction of the stylus 6 on the record tablet 10, there is in general a component of frictional force urging the stylus laterally out of the spirally directed record groove 31, Fig. 2. This component of force varies with the angular position of the arm 3 and becomes zero at only one position of the arm, which may be called a neutral position, as indicated by the line 5, 12, Fig. 2, and is that position of the arm in which the vertical plane including the point of the stylus 6 and the vertical pivot axis 5, 5, is tangent to the groove under the stylus.

When the arm 3 is on either side of said plane, the lateral frictional component increases with the angle made with the plane, and is a maximum at the extreme outer position 5, 13 and the extreme inner position 5, 14. The direction of the lateral component is toward the neutral 5, 12 when the direction of travel of the groove under the stylus, is away from the vertical axis 5, 5, as indicated by the full line arrows in Fig. 2, at 13 and 14, respectively. When the direction of groove travel is reversed, the direction of the lateral force is reversed as indicated by the dotted arrows at 13 and 14, respectively.

These and other disturbing forces, including those due to accidental jarring of the phonograph, or due to gravity when the turntable or record disk is not in a true horizontal position, are likely to increase any tendency for the stylus to dislocate from its desired groove position.

The scanning aid device 15 is provided to counteract the described undesirable tendencies and difficulties of the scanning operation, and to improve the scanning movement of the wave transmitting or reproducing stylus of the phonograph. Device 15 is remote from the vertical pivot axis 5, 5, and is disposed in predetermined relation with the main stylus 6. The elastically flexible bridge span 16 supports the rigid auxiliary stylus 17, which preferably has a sapphire or other long life type of point. The ends of the

span 16 are preferably supported by including the span in a closed, elastically deformable or extensible loop 15, the entire loop being of soft elastic plastic material, such as rubber or like material, molded or otherwise formed to have dimensions permitting the loop conveniently to encircle the stylus carrying unit 1 and to make a gripping engagement therewith. Stylus 17 is supported by imbedding its upper or unpointed end directly in the material of span 16. Span 16 is preferably placed under slight tension when attached to unit 1, to insure of a positive normal position of the span and to provide the desired flexibility. One or more of the inside dimensions of the loop 15, before assembly with unit 1, are made smaller than the corresponding dimensions of the portion of unit 1 to be encircled, in order that the elastically deformable loop 15 may be stressed sufficiently when conforming with the shape of unit 1, to provide suitable gripping force to hold the loop and stylus 17 in their desired predetermined relation with stylus 6, and to provide the desired tension in span 16. The described form of loop 15 may be conveniently assembled with or removed from unit 1 by simply stretching the loop sufficiently to allow it to pass over the end of unit 1 and stylus 6. The plane of the loop when in assembled position is substantially vertical, the longitudinal axis of the span being substantially horizontal and transverse to the main scanning direction of the styluses 6, 17.

In order that span 16 may be free to yield by flexing vertically and deflecting torsionally, a spacer 18 is provided at each end of the bridge span, the spacers 18 being integral with the loop 15 and projecting from the loop into the opening thereof, thus spacing the span from the bottom of unit 1.

Span 16 and stylus 17 are preferably positioned slightly in advance of stylus 6 in the main scanning direction of the styluses over disk 10, this direction being opposite to that of the travel of the disk under the stylus. The middle portion of span 16 is positioned close to, but out of contact with stylus 6 and its vibratory supporting means, in order to bring the support for stylus 17 close to stylus 6 without interfering with the vibration and normal movement of stylus 6 in its support, this relation being indicated in Fig. 1.

It will be seen that the line between the point of reproducing stylus 6 and the point where the stylus projects from its support, is inclined to the disk 10 at an acute angle pointing in the direction of disk travel under the stylus, in accordance with usual practice in the art, while the corresponding line between the point where stylus 17 projects from the loop span 16 and the point of stylus 17, also is inclined to the disk and makes an acute angle therewith pointing in the direction of disk travel under stylus 17. In its simplest and preferred form, stylus 17 is approximately straight and is positioned with its axis in a vertical plane including the pivot axis 5, 5, when subjected to no outside force.

Pilot stylus 17 scans the disk 10 with less wear to the stylus and the record and less load on the disk than is produced by stylus 6, since stylus 17 acts as a smaller mass and is free to vibrate in its elastic support 16 without being called on to reproduce the record waves for transmission. The wear and the load produced by stylus 17 may be still further reduced by making the angle of inclination of the stylus to the disk, smaller than in the case of stylus 6. The angle of inclination

of reproducing stylus 6 should be large enough to permit of suitable reproduction of the higher frequency components in the record waves, whereas the angle of pilot stylus 17 may be smaller, since it is not limited by any such reproducing requirement.

The point of stylus 17 is preferably located outside of the vertical plane defined by the longitudinal axis of the span 16 when the reproducing head 2 is in reproducing position, this plane being the plane of the loop when the span forms a part of the loop, as in Figs. 1 to 4. One advantage of this relation is that the points of the styluses 6 and 17 may be positioned close together without the span 16 being too close to stylus 6. An effective arrangement for this purpose is obtained when the point of stylus 17 is outside of the vertical projection of span 16 on the horizontal plane through the point of stylus 17, and stylus 6 is in its reproducing position as shown in Fig. 1. It will be seen that stylus 17 projects outwardly from loop 15 in a direction diverging from the plane of the loop. Bridge span 16 and stylus 17 are preferably located a predetermined distance in advance of reproducing stylus 6 in the main scanning direction of the styluses to avoid encroachment on stylus 6, but it will be understood that stylus 17 may be located behind stylus 6 in some cases, for example where there is more room for the bridge supporting means in that location.

Stylus 17 is also preferably spaced to one side of stylus 6 a predetermined distance radially of disk 10, such as a distance equal to one or a few groove spacings. In one case where adjacent grooves were spaced about five thousandths (.005) of an inch apart, the predetermined distance between styluses 17 and 6 laterally of the grooves of the disk, was found to be satisfactory when equal to about ten groove spacings or about fifty thousandths (.050) of an inch. In general, stylus 17 may be located on either side of stylus 6 laterally of the grooves, or in other words laterally of the main scanning direction, as shown by either stylus 17 or 17' relatively to stylus 6 in Fig. 6, but is preferably on the advance side, that is, the side of stylus 6 toward which the sound head 2 feeds across the grooves, and for this purpose stylus 17 may again be on either side of stylus 6, depending on whether the disk is scanned in a radially inward or outward direction.

By placing stylus 17 in advance of stylus 6 radially of disk 10, with the described spacing between the styluses, it is possible in the case of a disk having a series of discontinuous record grooves, representing separately dictated or interrupted recordings spaced relatively close together, for the stylus 17 to ride into and engage a starting portion of one of the grooves before stylus 6 reaches the end of the previous groove. Stylus 17 may thus serve to pilot or guide stylus 6 over the blank ungrooved space between two successive recordings, so that stylus 6 may be led into the desired groove without requiring manual resetting of the sound head position.

The section of bridge span 16 between vertical lines A—A and B—B in Fig. 5, may be substituted for the similar section between lines A—A and B—B in Fig. 4, to provide two or more styluses 17, 17', in place of the single stylus 17 of Fig. 4. The two styluses 17, 17' are preferably spaced laterally equal distances from stylus 6, as shown in Fig. 6, so that they may propel stylus 6 radially of disk 10 while crossing a larger

blank space between recordings than would be possible with the single pilot stylus 17 of Fig. 4. It will be understood however that the spacing between stylus 6 and the styluses 17, 17' may be unequal, if desired.

Figs. 7, 8 and 9 show a relatively short, block-shaped form of bridge span 16 of soft elastic rubber, or like material, with the ends of the span supported in a different manner from that of Figs. 1 to 4. At each end of span 16, a groove 30 is provided, extending across the end of the span, the span being supported by a pair of tongues or flanges 19, one of which fits into each of the pair of grooves 30, 30, and presses into the same with sufficient force to hold the ends of the bridge span positively in a fixed position. The tongues 19 form the inwardly directed ends, respectively, of a pair of brackets 20, 20, projecting downwardly from the rigid supporting plate 21, which is attached to the lower side of unit 1 by any suitable means, such as screws 22 passing through holes 23 in plate 21 and threaded into unit 1. It will be seen that brackets 20, 20 serve as spacers to hold the upper surface of span 16 spaced below the bottom side of unit 1, so that the span may be free to yield by flexing vertically or deflecting torsionally, as in the case of span 16, Figs. 1 to 4.

It will be understood that two pilot styluses 17, 17', as described in connection with Figs. 5, 6, or the substitute form of single pilot stylus 17, described in connection with Fig. 4, may be utilized in the span 16 of Fig. 7. Fig. 8 shows a side view of the Fig. 7 type of span support as it appears when utilizing either the single pilot stylus 17 of Fig. 4, or the double form of Fig. 5, the stylus 17 being directly in front of stylus 17' when viewed as in Fig. 8.

The bridge 16 form of support for stylus 17, as described in connection with the drawing, has been found to offer several advantages over various other forms of support, one advantage being that the bridge provides an efficient balanced support for the pilot stylus and provides a balanced control of the position of the pilot stylus by acting directly between the unit 1 and each side of the pilot stylus, thereby tending to minimize the introduction of unwanted components of force tending to move the sound head unit in undesired directions as a result of distortion of the pilot stylus support when yielding to up and down movements in the level of the record surface, or as a result of eccentricities in the record groove causing irregular directions of groove travel under the stylus, or as a result of other disturbing forces. For example, by employing a bridge to support the pilot stylus in a balanced manner from each side of the stylus, it will be seen that the stylus avoids the undesirable tendency to move in an arc around merely one end of the stylus support, as would be the tendency if the stylus were yieldingly supported wholly from one side alone. When the record grooves are packed very closely together for the sake of compactness and consequently are by necessity made very shallow, and when the grooves offer only a relatively small retaining force to hold either the reproducing stylus or the pilot stylus in its desired groove, as in the case of shallow embossed grooves in a plastic record disk, as well as in other cases, the bridge form of pilot stylus support has been found to be particularly advantageous.

The bridge type of pilot stylus support lends itself to compact construction, and as combined

in the preferred or loop form, is particularly adapted for convenient attachment to a sound head unit without requiring the use of any tools or complicated operations, and without requiring any machine operation on or alteration in the original construction of the unit to which it is applied. The loop form is therefore particularly convenient for attachment to phonographs which are to be conditioned for reproducing records offering less stylus tracking guidance than the records for which the phonographs were originally manufactured.

When the bridge 16 is supported directly from the vertically rigid part 3 of the unit 1, instead of directly from the vertically yieldable part 2 of unit 1, the pressure of stylus 6 on the disk 10 is not affected by the pressure of stylus 17 on the disk.

It will be understood that the material employed in the span 16 and the loop 15, may be of any suitable variety other than plastic, provided the bridge form is maintained with its elastic and balanced characteristics similar to those of the elastic bridge 16. The bridge 16 and auxiliary stylus 17 may in general be advantageously applied, not only to a reproducing arm unit, but to any type of stylus propelled sound head carriage where the stylus propelling force needs to be supplemented or is discontinuous, or where an auxiliary stylus is to be combined for any purpose with the main transmitting stylus. Although stylus 17 has been described as being preferably a rigid stylus supported from an elastic material, it will be understood that for some situations where a flexible auxiliary stylus or a plurality of them, such as bristles in brush-like form, are to be employed, either of the described forms of bridge 16, shown in Figs. 1 to 4, or 7, 8, may be employed to provide a compact, convenient and efficient form of support. The auxiliary stylus 17, while preferably located in advance of and to one side of stylus 6, may be placed to track in the same turn of the groove as stylus 6, either in advance of or behind stylus 6 in the scanning direction, in cases where the advantages of the preferred position of stylus 17 is not important.

While the invention has been described as being of particular utility in connection with a phonograph sound head of the reproducing type, it will be seen that the described attachment may also be applied to a sound head of the recording type for the purpose of aiding the tracking of the recording stylus on a pregrooved record blank of the type described in U. S. Patent No. 1,522,547 to B. F. Roehrig, or for guiding the recording stylus advancing over an ungrooved surface of a record blank while the auxiliary stylus follows the groove already produced by the recording stylus, it being necessary merely to provide a starting groove in the desired direction between the points where the recording and auxiliary styluses engage in contact with the record, the starting groove being of the form shown for example in U. S. Patent No. 1,959,423 to H. C. Harrison. The described attachment may also be used in various other combinations where a conveniently mountable, simple and compact auxiliary stylus is desired for scanning a record tablet.

The form of the devices may be varied considerably from the precise form described herein by way of illustration without departing from the invention as set forth in the appended claims.

I claim:

1. In a phonograph employing a record having a pair of recorded grooves separated by a smooth

ungrooved section, a reproducer head carrying an inclined reproducing stylus for scanning said record, and an auxiliary non-reproducing pointed pilot stylus of rigid material resiliently carried by said head and offset from said reproducing stylus by a distance equal to a whole number of grooves said pilot stylus being also inclined to said record and extending in the same general direction as said reproducing stylus, whereby the blank ungrooved section between said pair of grooves will be bridged automatically without requiring manual setting of said reproducer head.

2. In a phonograph employing a record having a pair of recorded grooves separated by a smooth ungrooved section, a reproducer head carrying an inclined reproducing stylus for scanning said record, and an auxiliary non-reproducing pointed pilot stylus of rigid material resiliently carried by said head and offset from said reproducing stylus by a distance equal to a whole number of grooves, said pilot stylus extending in the same general direction as said reproducing stylus and inclined to said record with a smaller angle.

3. In a device for attachment to a phonograph stylus-carrying unit for aiding the scanning of said stylus in the grooves of a phonograph record, a closed elastic rubber loop encircling said unit, certain of the inside dimensions of said loop being smaller than the corresponding dimensions of the encircled portion of said unit, said loop having a gripping engagement with said unit, and an auxiliary groove-engaging pointed stylus supported by said loop for assisting in holding the main stylus in its track.

4. A device according to claim 3 in which said loop includes a span having means for spacing said span from said stylus-carrying unit, said means including a pair of spacers, one at each end of said span and projecting from said loop into the opening of the loop to permit vertical and torsional deflection of said auxiliary stylus.

5. In a device for attachment to a phonograph stylus-carrying unit for aiding the tracking of said stylus in the grooves of a phonograph record, a bridge of elastic resilient material having bearings on said unit at a pair of spaced points and carrying an auxiliary non-reproducing pilot stylus in vertically and torsionally deflectable relation to said grooves, said pilot stylus being spaced a predetermined distance to one side of said main stylus laterally of the scanning direction thereof to bridge over the blank ungrooved spaces between two successive recordings.

6. In a device for attachment to a phonograph stylus-carrying unit for aiding the tracking of said stylus in the grooves of a phonograph record, a bridge of elastic resilient material having bearings on said unit at a pair of spaced points and carrying a pair of auxiliary non-reproducing pilot styluses spaced laterally in advance of and behind the main reproducing stylus respectively by distances equivalent to whole numbers of grooves.

7. In a device for attachment to a phonograph reproducing stylus for aiding the tracking of said stylus in the grooves of a phonograph record, a bridge of elastic resilient material attached to said unit, an auxiliary pointed pilot stylus supported by said bridge and offset from said reproducing stylus by a distance equal to a whole number of grooves, said pilot stylus being of smaller mass than said reproducing stylus so as to reduce the wear and load upon said record.

CERTIFICATE OF CORRECTION.

Patent No. 2,328,862.

September 7, 1943.

LINCOLN THOMPSON.

It is hereby certified that error appears in the printed specification of the above numbered patent requiring correction as follows: Page 4, second column, line 65, claim 7, after the word "stylus" insert --unit--; and that the said Letters Patent should be read with this correction therein that the same may conform to the record of the case in the Patent Office.

Signed and sealed this 26th day of October, A. D. 1943.
